HIS ATTORNEY

UNITED STATES PATENT OFFICE.

ARTHUR F. POOLE, OF PELHAM MANOR, NEW YORK, ASSIGNOR TO REMINGTON ACCOUNTING MACHINE CORPORATION, OF NEW YORK, N. Y., A CORPORATION OF NEW YORK.

CALCULATING MACHINE.

Application filed August 31, 1922, Serial No. 585,445.

To all whom it may concern:

Be it known that I, ARTHUR F. POOLE, citizen of the United States, and resident of Pelham Manor, in the county of Westchester and State of New York, have invented certain new and useful Improvements in Calculating Machines, of which the following is a specification.

This invention relates to improvements in calculating machines which comprise registering mechanism that includes a series of register wheels and positive carrying mechanism that is actuated by register wheels.

The object of the invention is to overcome trouble caused by the spiral which is developed in carrying operations, clearing operations and some others.

The invention consists of rectifying mechanism which acts on register wheels and coacts with the carrying mechanism in any carrying operation when all, or more than a few, of the register wheels are turned, and the construction of which is hereinafter described and specified in the claims.

On the accompanying two sheets of drawings on which like reference numerals designate like parts of the different views,

Figure 1 is a right side elevation of parts and a vertical section of parts of a machine embodying the invention, the mechanism shown being next to the front of the machine and its parts being in their normal positions.

Figure 2, a fragmental right side elevation and vertical section of mechanism shown in Fig. 1, parts thereof being in positions to which they move in operation; and

Figure 3, a fragmental front elevation of some of the framework and mechanism including parts shown in Fig. 2, and in the same positions as in Fig. 2.

The machine partly illustrated in the drawings is a Remington accounting machine in which this invention has been embodied. While the invention was made especially to improve the Remington machine and is shown only in the form in which it is embodied therein, it is not my intention to limit the invention by requiring it to have this particular form, or a form that would exclude it from machines not made by the Remington Company.

The Remington accounting machine, substantially as now manufactured, and including all of the old mechanism which is shown herein, is described in United States Letters Patent No. 1,270,471, granted June 25, 1918, to the assignee of John C. Wahl. As this specification, supplemented by the description contained in said patent, describes the claimed invention incorporated in a combined typewriting and computing machine and describes the manner of constructing and using the invention and explains the principle thereof, and the best mode yet contemplated of applying the principle, it is believed not to be necessary to illustrate and particularly describe the whole machine in this application.

The registering mechanism of the machine is contained in the totalizer or totalizers. The totalizer 1 (Fig. 1) is a vertical totalizer or column totalizer, the construction and operation of which are described in said patent. The support 2, to which the totalizer is attached at the back, is the main or vertical trunk which the patented machine contains and which is connected by arms at its ends to the typewriter carriage and travels with it when the carriage steps from right to left, and returns with it when the carriage is drawn to the right. The series of register wheels mounted on shaft 3 includes the dial wheels on which numbers are registered so that they may be read at the sight-opening 4 in the casing, each of these wheels being composed of a dial 5 and pinion 6 fast together. Gear 7 is one of the series of idle gears which engage with the pinions of the dial wheels, this series of gears being mounted on shaft 8. The gear wheels 9 mounted on shaft 10, each having thirty marginal teeth and three carrying teeth 11 and including a locking disk 12 having three scallops 13, are the carrying wheels that constantly engage with idle wheels 7 and successively engage with the master wheel as the totalizer travels over it. The dial wheels, idle wheels and carrying wheels are shown herein in the positions which they occupy when the totalizer is clear, or in other words, when a full row of zeros is visible through the sight-opening.

The gear 14, which is fast on star wheel 15, is one of the gears on which the carrying teeth 11 act, so that as any dial wheel except

that of highest denomination turns from "9" to "0" in an adding operation or from "0" to "9" in a subtracting operation, the carrying wheel of that dial imparts one-thirtieth of a rotation to the carrying wheel of next higher order, the motion being transmitted through the gear on which the carrying tooth acts, the star wheel to which that gear is affixed and a gear fixed to the star wheel 10 on its left face and meshing with the carrying wheel of higher order; the adjacent scallop in the locking disk of the driving carrying wheel allowing the star wheel then to turn. The arm 16 mounted on shaft 17 15 and connected to fixed cross rod 18 by spring 19 supports stud 20 which projects from the right side of the arm and on which is mounted star wheel 15 with the gears that are fast on it. The star wheel 21 is one of 20 the rear group of star wheels that alternate with those of the front group and that are mounted on arms supported by shaft 22, these arms being similar to the arm 23 to which is affixed dog 24 that acts on the 25 carrying wheel of lowest order.

Parts of the actuating mechanism which are shown or partly shown herein, and the construction, arrangement and operation of which said Wéhl patent describes, are link 30 25, fan 26, universal bar 27, rock shaft 28, arm 29, link 30, master deg cam 31, master dog 32, master wheel 33, sector shaft 34, spirally arranged arms 35, goose-neck 36, arm 37 and master wheel dog 38.

Although manufactured Remington machines contain devices that prevent the spiral from seriously impairing the action of the totalizers which are ordinarily used, yet that means is not a remedy for all of 40 the trouble which this invention is intended to overcome and would be of but little utility in some totalizers which it is desirable more or less frequently to use. The spiral is developed to the greatest extent 45 when motion is imparted from the carrying wheel of lowest denomination to all of the other carrying wheels of the series. Since there is and must be a small amount of lost motion in the gearing that connects 50 any carrying wheel with the next, there is a multiple of that amount in the whole train of gearing that extends from the lowest to the highest carrying wheel, so that the longer is the series of carrying wheels 55 the greater is the amount of lost motion in the carrying gear train. In a totalizer containing a sufficiently long series of wheels, the spiral would absorb all of the motion derived from a carrying tooth of the lowest 60 carrying wheel so that not any of it could be imparted to the highest carrying wheel.

Probably trouble caused by the spiral in clearing operations is more annoying than that caused by it in carrying operations, 65 since clearing operations are frequently per-

formed, whereas carrying operations in which carrying is done to several wheels at a time are performed only occasionally or rarely, the spiral not occurring so as to be troublesome except when a number registered at the sight-opening contains either nines or zeros.

By means of this invention a machine of which it is a part, although the totalizer or each totalizer shall contain an uncommonly long series of dial wheels and an equally long series of carrying wheels forming parts of a long carrying gear train, is made effective to perform carrying operations and clearing operations without troublesome interference from the spiral whether all or some only of the carrying wheels are turned in any operation.

The new mechanism added to said patented machine and in combination with parts thereof constituting the invention claimed herein, consists essentially of the arm 39, pin 40, shaft 41, arms 42 and 43, cross rod 44, forked arm 45 and four aligning dogs 46, 47, 48 and 49. Arm 39 is fast on the arbor 50, this arbor and the master dog cam 31 being fast together and the arbor having bearings in plates 51 and 52 of the framework of the actuating mechanism. Pin 40 is fast on arm 39 and projects therefrom through slot 53 in frame plate 52, and between the branches of forked arm 45, the pin fitting loosely in the fork. Shaft 41 has bearings in frame plates 52 and 54. Arms 42 and 43 and forked arm 45 are rigidly attached to this shaft. Preferably the forked arm and arm 42 are made in one piece and have the common hub 55 which may fit tightly on and be pinned to the shaft. Cross rod 44 is fast at its ends in arms 42 and 43. Shaft 41, arms 42 and 43 and cross rod 44 are parts of a frame or bail that fits loosely between frame plates 52 and 54, and can be rocked on the axis of shaft 41 by the action of pin 40 on forked arm 45 as the pin moves up and down in slot 53, and when the bail is so rocked cross rod 44 swings forward and backward.

Aligning dogs 46, 47, 48 and 49 fit loosely in slots cut in cross bar 56 of the framework of the actuating mechanism. Behind these dogs is a keeper 57 which crosses the slots and is fastened to the cross bar, preferably by screw 58 and others like it. The walls of these slots and the keeper form slideways in which the straight portions of the dogs are movable freely up and down. Each dog has at its upper end a tooth formed on it and shaped to fit in the interdental spaces of the carrying wheels 9 of the totalizer, and has below the straight portion a slotted portion which extends under the cross bar and keeper and with which cross rod 44 engages. The slotted portions 59, 60, 61 and 62 of these dogs are alike ex-

cept that each of the slots 63, 64, 65 and 66 differs slightly from any of the others. Cross rod 44 passes through these slots, the upper edge of each slot resting on the cross rod so that each dog is supported by the cross rod. When the position of the cross rod is its normal position, indicated in Fig. 1, the dogs then being in their highest and normal positions, the teeth of the dogs 10 are all at the same elevation and in alignment, the elevation being such and the dogs being so spaced that if the master wheel engages the carrying wheel of lowest order each dog fully engages with a carrying 15 wheel. When the position of the cross rod is that shown in Fig. 2, the teeth of the dogs are all in alignment at an elevation which prevents them from engaging with the carrying wheels. The upper edge of slots 63 20 in dog 46 is straight and slopes upward from the point where it rests on rod 44 when the dogs are in their normal positions clear to its outer or front end. The upper edge of each of the slots 64, 65 and 66, in dogs 47, 25 48 and 49, respectively, is straight and slopes upward from the point where it rests on rod 44 when the dogs are in their normal positions to a point near its front end and thence extends forward horizontally or 30 thereabout to its front end. The lower edge of each of these four slots is parallel to its upper edge. The horizontal portion of slot 64 is a little shorter and the corresponding portion of slot 66 is a little longer than the 35 corresponding portion of slot 63. The sloping portion of slot 64 recedes a little, that of slot 65 a little more, and that of slot 66 still a little more, as they approach the horizontal portions respectively, from the plane 40 that is parallel to the edges of the front portion of slot 63 and that contains the axis of the cross rod when the positions of the rod and dogs are those shown and indicated in Fig. 2, in which the lower edges of all of the 45 slots and the upper edge of slot 63 are shown in full lines, and the upper edges of slots 64, 65 and 66 are indicated by dotted lines. Hence, when the cross rod and dogs are moved from those positions, the cross rod as 50 it swings backward acts instantly on dog 46 and thereafter acts successively on dogs 47, 48 and 49, so that the upward movement of dog 47 is delayed a little, that of dog 48 a little more, and that of dog 49 still a little 55 more. After the cross rod passes from the horizontal portion of slot 66 in dog 49 it moves all of the dogs upward together but at different speeds to their highest positions. Cross bar 56 has in its lower side slots 67, 68, 69 and 70, and when the dogs are in their highest positions their lower portions extend into these slots. The guide slots shown in the cross bar are so located that when the master wheel engages the carrying wheel of 60 lowest order and the aligning dogs are in

their normal positions, dog 46 engages the fourth carrying wheel from the lowest and each other dog engages the third carrying wheel from that engaged by the next dog on the right. When the master wheel engages 70 any one of the carrying wheels of the three highest orders, the aligning dogs do not engage any wheels, but as the carriage steps toward the left, said dogs come into use as 75 needed. Whenever the fan 26 or any other fan of the series is actuated as described in said Wahl patent, arm 39 is swung so that pin 40 moves upward from its lowest position shown in Fig. 1 to its highest position shown 80 in Fig. 2, motion being imparted to this arm from the fan through universal bar 27, rock shaft 28, arm 29, link 30, master dog cam 31 and arbor 50. As pin 40 so moves it acts through forked arm 45 on the 85 bail comprising cross rod 44 and the cross rod swinging forward draws down the aligning dogs. When at the end of the down stroke of a key the master dog cam and other parts connected with it return to their 90 normal positions, pin 40 acting on forked arm 45 forces rod 44 and the aligning dogs back to their normal positions. As the totalizer travels step by step to the left or is drawn to the right, from side to side of the 95 master wheel, the carrying wheels clear the teeth of the aligning dogs as they clear the teeth of the master wheel, the tooth of each dog extending into an interdental space when any carrying wheel passes over the 100 dog.

Figs. 2 and 3 illustrate the rectifying mechanism just after the master wheel has acted on the carrying wheel of lowest order and when a row of zeros is registered at the 105 sight opening of the totalizer. The operation might be one in which carrying is done to all carrying wheels above the lowest, or one in which the totalizer is cleared by adding to a registered number the complement of that number. The fan 26 is about to end its action on universal bar 27, the numeral key having nearly but not quite reached the limit of its downward movement, dog 38 is 110 disengaged from the master wheel, master dog 32 is holding dog 24 disengaged from the carrying wheel, the aligning dogs 46, 47, 48 and 49 are held down by cross rod 44, and the master wheel still engages the lowest 115 carrying wheel. As fan 26 passes from contact with the universal bar, and as the key about reaches the end of its stroke, the universal bar, the master dog cam, the master dog, the dogs 24 and 38 and the aligning dogs return to their normal positions, and thereafter and while the key is rising the totalizer steps. The aligning dogs turn the 120 wheels on which they act enough to compensate for those losses of movement which are parts of the loss occurring in the spiral, so 125 130

that at the end of the operation the figures visible at the sight opening form a true line. As dog 46 engages and rectifies the carrying wheel which is over it and which is the fifth from the right end of the series, that wheel acts through a portion of the carrying gear train on the sixth, seventh and eighth carrying wheels, and instantly thereafter dog 47 rectifies the eighth wheel which 10 then acts on that part of the carrying train which includes the ninth, tenth and eleventh carrying wheels, and then dog 48 rectifies the eleventh wheel which acts on the carrying train to and including the fourteenth carrying wheel, which is then rectified by dog 49 and acts on that part of the carrying train which includes the carrying wheel of highest order. The aligning dogs move 20 upward very quickly so that each of them strikes a tooth of its carrying wheel 9 a light blow. Said dogs not only act successively as described but also act together as they reach their highest positions.

The number of aligning dogs might be greater or smaller than the number shown, or other modifications of the described rectifying mechanism might be made in embodying the invention in other machines, and various changes may be made in the details 30 of construction and arrangement without departing from my invention.

What I claim as new and desire to secure by Letters Patent, is:—

1. In a calculating machine, the combination with key operated actuating mechanism in which a master gear wheel is included, a carrying gear train wholly supported in a totalizer and including wheels which the master wheel engages successively, and means whereby a relative stepping movement of the master wheel and gear train is produced after a key is depressed, of wheel aligning means which is supported in the framework of the actuating mechanism and connected to a part of that mechanism and includes wheel engaging portions which, when they are in their normal positions, stand in alignment with interdental spaces of wheels of said gear train, movement from their normal positions being produced by depression of a key and movement to their normal positions being produced by return to normal position of said part of the actuating mechanism at the end of the key stroke.
2. In a calculating machine, the combination with key operated actuating mechanism in which a master gear wheel is included and which is supported in framework that is rigidly connected to the machine base, a carrying gear train wholly supported in a traveling totalizer and including wheels which the master wheel engages successively, and means whereby a stepping movement of the totalizer is produced after a key is depressed, of wheel aligning means which is supported in said framework and connected to a part of the actuating mechanism and includes wheel engaging portions that stand, when they are in their normal positions, in alignment with interdental spaces of wheels of said gear train, movement from their normal positions being produced by depression of a key and movement to their normal positions being produced by return to normal position of said part of the actuating mechanism at the end of the key stroke.
3. In a calculating machine, the combination with key operated actuating mechanism in which a master gear wheel, a universal bar, and a rocking device connected with said bar are included and which is supported in framework that is rigidly connected to the machine base, a carrying gear train wholly supported in a traveling totalizer and including wheels which the master wheel engages successively, and means whereby a stepping movement of the totalizer is produced after a key is depressed, of wheel aligning means which is supported in said framework and connected to an arm fast on said rocking device and includes wheel engaging portions that stand, when they are in their normal positions, in alignment with interdental spaces of wheels of said gear train, movement from their normal positions being produced by depression of a key, and movement to their normal positions being produced by retraction of said arm as the universal bar returns to its normal position at the end of the key stroke.
4. In a calculating machine, the combination with key operated actuating mechanism in which a master gear wheel is included, a carrying gear train wholly supported in a totalizer and including wheels which the master wheel engages successively, and means whereby a relative stepping movement of the master wheel and gear train is produced after a key is depressed, of wheel aligning means which is supported in the framework of the actuating mechanism and connected to a part of that mechanism and engages wheels of said gear train when all parts of the wheel aligning means and actuating mechanism are in their normal positions and the master wheel meshes with the carrying wheel of lowest order, movement of the wheel aligning means from the wheels of the train being produced by depression of a key before the key transmits motion to the master wheel and movement to the wheels of the train being produced by return to normal position of said part of the actuating mechanism at the end of the key stroke, after arrest of the master wheel.
5. In a calculating machine, the combination with key operated actuating mechanism in which a master gear wheel is included, and which is supported in framework that is rigidly connected to the machine base, a carry-

ing gear train wholly supported in a traveling totalizer and including wheels which the master wheel engages successively, and means whereby a stepping movement of the totalizer is produced after a key is depressed, of wheel aligning means which is supported in said framework and connected to a part of the actuating mechanism and engages wheels of said gear train when all parts of the wheel aligning means and actuating mechanism are in their normal positions and the master wheel meshes with the carrying wheel of lowest order, movement of the wheel aligning means from the wheels of the train being produced by depression of a key before the key transmits motion to the master wheel, and movement to the wheels of the train being produced by return to normal position of said part of the actuating mechanism at the end of the key stroke, after arrest of the master wheel.

6. In a calculating machine, the combination with key operated actuating mechanism in which a master gear wheel is included, a carrying gear train wholly supported in a totalizer and including wheels which the master wheel engages successively, and means whereby a relative stepping movement of the master wheel and gear train is produced after a key is depressed, of wheel aligning means which is supported in the framework of the actuating mechanism and connected to a part of that mechanism and includes aligning dogs that are separated by spaces each equal in width to a plurality of letter spaces and that stand in alignment with interdental spaces of wheels of said gear train when the wheel aligning means is in its normal position, movement of the dogs from their normal positions being produced by depression of a key and movement to their normal positions being produced by return to normal position of said part of the actuating mechanism at the end of the key stroke.

45. 7. In a calculating machine, the combination with key operated actuating mechanism in which a master gear wheel is included and which is supported in framework that is rigidly connected to the machine base, a carrying gear train wholly supported in a traveling totalizer and including wheels which the master wheel engages successively, and means whereby a stepping movement of the totalizer is produced after a key is depressed, of wheel aligning means which is supported in said framework and connected with part of the actuating mechanism and includes aligning dogs that are separated by spaces each equal in width to a plurality of letter spaces and that stand in alignment with interdental spaces of wheels of said gear train when the wheel aligning means is in its normal position, movement of the dogs from their normal positions being produced by depression of a key and movement to their

normal positions being produced by return to normal position of said part of the actuating mechanism at the end of the key stroke.

8. In a calculating machine, the combination with key operated actuating mechanism in which a master gear wheel is included, a carrying gear train wholly supported in a totalizer and including wheels which the master wheel engages successively, and means whereby a relative stepping movement of the master wheel and gear train is produced after a key is depressed, of wheel aligning means which is supported in the framework of the actuating mechanism and connected to a part of that mechanism and includes a swinging rod and aligning dogs which slide in guides and are supported by said rod and at times engage with and act immediately on wheels of said gear train and on which the rod acts in its swinging movements, the gear train being higher than the rod and the motion of each dog from and to its wheel engaging position being downward and upward respectively.

9. In a calculating machine, the combination with key operated actuating mechanism in which a master gear wheel is included and which is supported in framework that is rigidly connected to the machine base, a carrying gear train wholly supported in a traveling totalizer and including wheels which the master wheel engages successively, and means whereby a stepping movement of the totalizer is produced after a key is depressed, of wheel aligning means which is supported in said framework and connected to a part of the actuating mechanism and includes a swinging rod and aligning dogs which slide in guides and are supported by said rod and at times engage with and act immediately on wheels of said gear train and on which the rod acts in its swinging movements, the gear train being higher than the rod and the motion of each dog from and to its wheel engaging position being downward and upward respectively.

10. In a calculating machine the combination with actuating mechanism in which a master gear wheel is included and which is supported in framework that is rigidly connected with the machine base, and a series of gear wheels which are supported in a traveling totalizer and included in a carrying gear train and which the master wheel engages successively as the totalizer travels past it, of wheel aligning means which is supported in said framework and connected to a part of the actuating mechanism and includes a swinging rod and aligning dogs that have fixed guides above the rod and include slotted portions below the guides and that are supported by the rod passing through the slotted portions and are movable upward by it into engagement with wheels of said series.

11. In a calculating machine the combination with actuating mechanism in which a master gear wheel is included, and a series of gear wheels which the master wheel engages successively and which are included in a carrying gear train supported in a totalizer, of wheel aligning means which is supported in the framework of the actuating mechanism and connected to a part of that mechanism and includes a swinging rod and aligning dogs that slide in guides and at times engage with and act immediately on wheels of said series, the dogs including wheel engaging teeth and having surfaces on which the rod acts as it swings and each of which extends between the rod and tooth of the dog and the shapes of which are such that the teeth of the dogs are equally distant from the rod when it is at either end of its movement and at other times are at distances from the rod and decrease in order from right to left.

12. In a calculating machine the combination with actuating mechanism in which a master gear wheel is included and which is supported in framework that is rigidly connected to the machine base, and a series of gear wheels which are supported in a traveling totalizer and included in a carrying gear train and which the master wheel engages successively as the totalizer travels past it, of wheel aligning means which is supported in said framework and connected to a part of the actuating mechanism and includes a swinging rod and aligning dogs that have fixed guides and contain slots through which the rod extends and include wheel engaging teeth that at times act on wheels of said series, each slot having an edge which extends between the rod and tooth of the dog and on which the rod acts from end to end of its movement and the shape of which is such that the teeth of the dogs are equally distant from the rod when it is at either end of its movement and at other times are at distances from the rod that decrease in order from right to left.

13. In a calculating machine, the combination with key operated actuating mechanism in which a master wheel, a universal bar, and a rocking device connected with said bar are included and which is supported in framework that is rigidly connected to the machine base, and a series of gear wheels which are supported in a traveling totalizer and included in a traveling gear train and which the master wheel engages successively as the totalizer travels past it, of wheel aligning means comprising an angularly movable shaft supported in said framework, a pair of arms and a slotted arm fast on said shaft, a cross rod fast in the arms of said pair, an arm fast on said rocking device, a pin fast in the last mentioned arm and engaging with the fork of the forked arm, and aligning dogs which are connected to and actuated by

said rod and at times engage with and act immediately on wheels of said series, the dogs being in their normal positions when said key operated universal bar is in its normal position and when the dogs engage said wheels.

14. In a calculating machine the combination with actuating mechanism in which a master wheel, a universal bar, and a rocking device connected with said bar are included and which is supported in framework that is rigidly connected to the machine base, and a series of gear wheels which are supported in a traveling totalizer and included in a carrying gear train and which the master wheel engages successively as the totalizer travels past it, of wheel aligning means comprising an angularly movable shaft supported in said framework, a pair of arms and a slotted arm fast on said shaft, a cross rod fast in the arms of said pair, an arm fast on said rocking device, a pin fast in the last mentioned arm and engaging with the fork of the forked arm, and aligning dogs that have guides in a frame bar above said cross rod and include slotted portions below the guides and that are supported by the rod passing through the slotted portions and are movable upward by it into engagement with wheels of said series.

15. In a calculating machine a set of wheel aligning dogs forming a row that extends from right to left and having fixed guides and each including a wheel engaging tooth at one end and a slotted portion made to fit on and extend across a swinging rod, the slots so differing in shape that said portions fit on the rod both when the teeth are equally distant from it and when they are at distances from it that decrease from right to left.

16. In a calculating machine a set of wheel aligning dogs forming a row that extends from right to left and having fixed guides and each including a wheel engaging tooth at one end and a slotted portion made to fit on and extend across a swinging rod, the slots so differing in shape that when the rod is at either end of its swinging movement the teeth are equally distant from it and when it is at different places between the limits of its movement the teeth are at distances from it that decrease from right to left.

17. In a calculating machine, the combination with key operated actuating mechanism in which a master gear wheel is included, a carrying gear train wholly supported in a totalizer and including wheels which the master gear wheel engages successively, and means whereby a relative stepping movement of the master wheel and gear train is produced after a key is depressed, of wheel aligning means which is supported in the framework of the actuating mechanism and connected to a part of that mechanism and

- includes aligning dogs that engage wheels of said gear train when the master wheel engages the wheel of lowest order in said train and the dogs and other parts of the wheel aligning means are in their normal positions, and that stand in their normal positions during each relative stepping movement of the master wheel and gear train.
18. In a calculating machine, the combination with key operated actuating mechanism in which a master gear wheel is included and which is supported in framework that is rigidly connected to the machine base, a carrying gear train wholly supported in a traveling totalizer and including wheels which the master wheel engages successively, and means whereby a stepping movement of the totalizer is produced after a key is de-
- pressed, of wheel aligning means which is supported in said framework and connected to part of the actuating mechanism and includes aligning dogs that engage wheels of said gear train when the master wheel engages the wheel of lowest order in said train and the dogs and other parts of the wheel aligning means are in their normal positions, and that stand in their normal positions during each stepping movement of the totalizer.
- Signed at the borough of Manhattan, city New York, in the county of New York, and State of New York, this 30th day of August, A. D. 1922.
